[57] CLAIM

The ornamental design for a medical dosage box, as shown and described.

DESCRIPTION

FIG. 1 is a front and top perspective view of a medical dosage box in the closed position showing my new design; FIG. 2 is a bottom perspective view in the open position; FIG. 3 is a bottom perspective view of an individual holder installed in the box in FIG. 5;

FIG. 4 is a bottom perspective view in the closed position; FIG. 5 is a top perspective view in the open position showing individual holders; and, FIG. 6 is a top perspective view of the subject matter of FIG. 3 with top open.

The individual holders in FIGS. 3 and 6 are illustrated separately for clarity of illustration.
